UNITED STATES PATENT OFFICE

2,112,312

ONE-PIECE SHROUDED HINGE MEMBER AND
METHOD OF FORMING SAMEHazor J. Smith, Longmeadow, Mass., assignor to
Moore Drop Forging Company, Springfield,
Mass., a corporation of Massachusetts

Application September 5, 1935, Serial No. 39,269

6 Claims. (Cl. 29—11)

This invention relates to hinges, and more particularly to a hinge for use on automobile doors and the like.

An object of the invention is to provide a cheap, simple, durable and commercially practical hinge of the above type.

Another object is to provide a one-piece shrouded hinge member.

Another object is to provide a simplified method for making a hinge of the above type.

Another object is to provide a one-piece hinge member having a unitary shroud and bushing.

Various other objects will be apparent as the nature of the invention is more fully disclosed.

15 A feature of the invention consists in the formation of a unitary hinge member from a one-piece blank which is adapted to form the bushings for the hinge pin and a shroud for concealing the hinge knuckle.

20 In one embodiment, this is accomplished by providing a blank having flanges formed on opposite edges thereof. These flanges are bent back over the body of the blank, and the blank is rolled to form a hinge knuckle in which the flanges constitute built-in bushings and the body constitutes a shroud. The hinge is formed with a minimum number of operations and, by reason of its 25 integral structure, is extremely durable.

Other features consist in the various details 30 of construction and combination of parts herein-after set forth.

The broader aspects of the invention will be better understood by referring to the following description, taken in connection with the accompanying drawing forming a part thereof, in which certain preferred embodiments of the invention are set forth in detail for purposes of illustration.

In the drawing,

Figure 1 is a plan view of the blank from which 40 the hinge member is made;

Figure 2 is an end elevation of the blank illustrating a step in the making of the hinge member;

Figure 3 is a plan view of the blank with the side flanges folded over to form the upper and 45 lower bushings;

Figure 4 is an end elevation of the hinge member as shown in Figure 3;

Figure 5 is a plan view of the formed hinge member;

50 Figure 6 is a longitudinal section thereof taken along the line 6—6 of Figure 5;

Figure 7 is a plan view of the hinged member;

Figure 8 is an end elevation thereof;

Figure 9 is a plan view of the assembled hinge; 55 and

Figure 10 is a section taken on the line 10—10 of Figure 9.

In the following description and in the claims, certain specific terms are used for convenience in referring to various details of the invention. 5 These terms, however, are to be given as broad an interpretation as the state of the art will permit.

Referring to the drawing more in detail, the hinge is shown as comprising a base or hinge 10 member (Figures 1 to 5) and a hinged member (Figures 7 and 8). The hinge member is made from a blank (Figure 1) comprising a body portion 10 having an aperture 11 formed therein, for the purpose to be described, and having a pair 15 of side flanges 12 formed on the opposite edges thereof. This blank may be stamped or cut from sheet metal in any desired manner.

In order to form the hinge member from the blank above described, the flanges 12 are first 20 bent upwardly, as indicated in Figure 2, and are then folded over the face of the body 10, as indicated in Figures 3 and 4.

The blank, with the flanges 12 thus folded over, 25 is then rolled to form a substantially cylindrical hinge knuckle 14 and a pair of overlapping flat sections 15 (Figures 5 and 6), the flanges 12 forming bushings 16 and the body portion forming a shroud 17. The flat sections 15 are provided with apertures 18 adapted to receive attaching screws. It is to be noted that the outer 30 surface of the hinge knuckle 14 does not backtrack on itself but is directly continuous with each of the outer surfaces of the flat section 15.

The blank may be rolled into the form above 35 described in any convenient manner, as by a die, which is adapted to form the hinge knuckle 14 with a predetermined external diameter. During the forming process the bushings 16 are caused to increase somewhat in thickness, since 40 the metal is free to expand only toward the center of the hinge knuckle. This increase in thickness provides clearance for the tongue of the hinged member, to be described.

The hinged member comprises a flat plate 20 45 (Figure 7 and 8) having a tongue 21 which is rolled into cylindrical form. The hinged member is preferably formed of a metal having the same thickness as the blank above described and may be cut or stamped therefrom in any convenient manner. It is also provided with apertures 22 adapted to receive fastening screws. 50

In assembling the two members, bushings 16 are reamed to receive the hinge pin. The hinged member is then placed in position with the rolled 55

tongue registering with the bushings 16 of the hinge member. Thereafter, a hinge pin 25 is passed through the bushings 16 and through the tongue 21.

5. It is to be noted that the aperture 11 provides clearance for the passage of the tongue 21 and also serves to limit the movement of the hinged member. In the form shown, for example, the hinge may open approximately 90° or until the tongue 21 engages the edge 26 of the aperture 11. It is to be noted that the increase in thickness of the metal of the bushings 16 serves to provide clearance between the inner surface of the shroud 17 and the tongue 21. The shroud 15 covers substantially the entire outer surface of the hinge knuckle, thereby concealing the tongue 21 and the built-in bushings 16. The hinge accordingly has integrally formed bushings and shroud, made from a one-piece blank by a minimum number of operations.

Obviously, the length of the flanges 12 should be such that the bushings 16 extend over as great a portion of the circumference as possible so as to provide the maximum bearing surface for the hinge pin and also to facilitate the proper positioning of the reamer. The size and position of the aperture 11 is determined by the size of the tongue 21 and the maximum opening of the hinge.

30. In some instances, only a single flat section 15 may be required. In that case, the hinge member may be made in the manner above described, but the flanges 12 may be located at the end of the blank which is made correspondingly shorter.
35. The hinged member 20—21 may be formed so that the portion 20 is cylindrical and still be within the spirit of my invention.

Although a specific embodiment of the invention has been disclosed for purpose of illustration, it is to be understood that various changes and substitutions may be made therein without departing from the scope of the invention, which is to be limited only in accordance with the following claims when interpreted in view of the 45 prior art.

I claim:

1. A one-piece hinge member formed from a blank comprising a body portion and a pair of side flanges at the two edges thereof, said flanges

being bent over said body portion to provide an extra thickness of metal at said edges, said blank being rolled to form a hinge knuckle with said flanges on the inside to form built-in bushings.

2. A one-piece hinge member formed from a blank comprising a body portion and a pair of side flanges extending from the two edges thereof, said flanges being bent over said body portion to provide an extra thickness of metal at the two edges, said blank being rolled to form a hinge knuckle with said flanges on the inside and under conditions such that the thickness of metal of said flanges is increased, whereby clearance is provided for a hinged member.

3. The method of forming a one-piece hinge member from a blank having a body portion and side flanges which comprises folding the flanges over against the body portion and rolling the adjacent portion of the blank to form a hinge knuckle with the flanges on the inside to form built-in bushings.

4. The method of forming a one-piece hinge member from a blank having a body portion and side flanges which comprises folding the flanges over against the body portion and rolling the adjacent portion of the blank to form a hinge knuckle with the flanges on the inside to form built-in bushings, while restricting the external diameter of the knuckle so that the bushings are caused to increase in thickness toward the center 30 of the knuckle, the body of said blank forming a shroud substantially completely enclosing said knuckle.

5. The method of forming a one-piece hinge member from a blank with an extra thickness 35 of metal at the two edges thereof which comprises rolling the blank to form a hinge knuckle with said extra thickness of metal on the inside to provide built-in bushings.

6. The method of forming a one-piece hinge member from a blank having a body portion and side flanges which comprises folding the flanges over against the body portion and folding the body to form overlapping flat sections and an intermediate rolled hinge knuckle with the 45 flanges on the inside of said knuckle to form built-in bushings.

HAZOR J. SMITH.
